UNITED STATES PATENT OFFICE.

SAMUEL S. DAVIS, OF SIDNEY, OHIO.

STEAM-BOILER.

No. 866,629.

Specification of Letters Patent.

Patented Sept. 24, 1907.

Application filed December 6, 1906. Serial No. 346,471.

To all whom it may concern:

Be it known that I, SAMUEL S. DAVIS, a citizen of the United States, residing at Sidney, in the county of Shelby and State of Ohio, have invented a new and useful Steam-Boiler, of which the following is a specification.

This invention relates to the construction of that class of steam boilers known as flashers; wherein small quantities of water are sprayed against heated metallic surfaces and instantly converted into steam.

The principal object of the invention is to provide a flasher in which the steam may be kept thoroughly dry and may be superheated, if necessary, to the point of decomposition, so as to form a dry gas.

15 A further object of the invention is to provide a boiler in which no water whatever will be retained within the boiler, so that the heat may be utilized for the purpose of raising the metal of the boiler to a high temperature.

20 A still further object of the invention is to provide a plurality of banks of flash tubes into which small quantities of water are sprayed alternately, the steam thus formed being conducted through auxiliary tubes for the purpose of superheating and drying the same.

25 A still further object of the invention is to provide novel means for feeding or forcing small quantities of water, together with air under pressure, alternately into the banks of tubes, the air serving in part as a means for atomizing and finely dividing the water.

30 With these and other objects in view, as will more fully hereinafter appear, the invention consists in certain novel features of construction and arrangement of parts, hereinafter fully described, illustrated in the accompanying drawings, and particularly pointed out 35 in the appended claims, it being understood that various changes in the form, proportions, size and minor details of the structure may be made without departing from the spirit or sacrificing any of the advantages of the invention.

40 In the accompanying drawings:—Figure 1 is an elevation of a steam boiler constructed in accordance with the invention, the outer shell or casing being shown in section. Fig. 2 is a transverse sectional elevation of the same. Fig. 3 is a detail plan view showing one of 45 the sets of flashers and the connections. Fig. 4 is a sectional elevation through one of the upper flasher tubes and one of the superheating tubes:

Similar numerals of reference are employed to indicate corresponding parts throughout the several figures 50 of the drawings.

The principal parts of the boiler are inclosed within an asbestos lined metal casing 10 including top and bottom plates 11 and 12, and side and end walls, the end walls 14 being connected by suitable longitudinal staybolts 15 so arranged as to permit convenient open-

ing of the casing when access is to be had to the interior thereof.

At the bottom of the casing is a suitable heating means 16 which may take the form of vapor or gas burners or any other kind of fuel may be used as desired.

The flasher tubes are arranged in two banks, the lowermost bank 18 having tubes of a less number than the upper bank 19; and the tubes of one bank are staggered with relation to those of the other, so that the products of combustion may pass between the tubes of the lower bank and impinge directly against those of the upper bank. Above the upper bank is a third set of tubes 20 which are staggered with relation to the tubes 19, and are preferably of a number greater than the number of tubes in either the bank 18 or the bank 19.

Arranged in front of the flasher tubes 18 and 19 are transversely extending feeder tubes 21 and 22, from which extend spraying nipples 23, these passing through suitable stuffing boxes 24 which fit within openings formed in hollow plugs 25 that are welded in the front ends of the flasher tubes. The nipples may be of any desired construction, but preferably are provided with minute openings at their inner ends, through which intermingled volumes of air and water are directed, the water being atomized or finely divided, and directed into contact with the heated walls of the tubes where it instantly flashes into steam.

The rear ends of the flasher tubes are provided with welded plugs 26 from which project nipples 27 that are connected to horizontally disposed pipes 29. Each of these tubes is closed at one end by a plug 31, and at the opposite end is connected to a vertically disposed tube 32, the latter being provided at its lower end with a blow off cock 33, and at its upper end with a safety valve 34 of any ordinary construction.

Connected to the vertical tube 32 is a third horizontal tube 36 which is connected by short nipples 37 to the rear ends of the upper bank of tubes 20, all of the steam formed in the lower flasher tubes 18 and 19 being conducted through the upper bank of tubes 20, and there partly dried and superheated. The front ends of the tubes 20 are connected to a transversely extending tube 38 which is connected to one end of the lowermost of a series of connected banks of tubes 40, these tubes being of a size much smaller than the flasher tubes, and being connected in a continuous series, the steam entering one end of the lowermost bank and escaping from the opposite end of the topmost bank and from there passing to the engine or other point. The smaller tubes extend completely across the upper portion of the combustion chamber, and the tubes of the different rows, being arranged in staggered relation, form barriers or baffles which will to some extent tend to retard the escape of the products of combustion, so that the tubes may be 110

very highly heated, and the steam from the flashers will be dried and superheated, the temperature being raised to any desired extent, sometimes to a point where the steam decomposes into its constituent elements and 5 forms a very dry gas under high pressure.

The water to be used in the formation of steam is supplied from a tank 50 which may be located at any convenient point. From the bottom of the tank leads a 10 valved discharge pipe 51 containing, also, a one way check valve 52, this pipe being connected to the lower end of the cylinder of a pump 53 which may be of any ordinary construction, the upward movement of the piston serving to draw water from the tank through the pipe 51 into the cylinder of the pump. The water is 15 discharged from the cylinder through a pipe 54 having a one way check valve 55, and is delivered into a small pressure reservoir 56, from whence it flows through a pipe 57 to a feed water heater 58, the latter being formed of a number of rows of tubes which are placed above the 20 superheating tube 40 and are exposed to the action of the products of combustion, so that the heat may be utilized to raise the temperature of the feed water in advance of the forcing of such water into the flasher tubes.

The chamber 56 is employed for the purpose of insuring 25 a steady flow of the feed water, this chamber being always maintained full by the action of the pump. Should there be any decrease in the quantity of steam used, and the supply of water fed to the boiler reduced, the pump 53 may continue to operate, and the surplus 30 water will return through a by-pass provided with a one way check valve 59. The heated water passes from the feed water heater 58 to a pipe 60 that is branched to form two discharges 61 and 62, the passage of water to these being under the control of independent valves 63. 35 The water discharges into tanks 64 and 65, respectively, and the tops of these tanks are open or provided with perforations 66 to permit the inflow of air to mingle with the water. Below the chambers 64 and 65 is a double acting pump 66', the opposite ends of the pump cylinder 40 being connected by pipes 67 and 68 to the chambers 64 and 65, respectively, and in each of these pipes is a one way check valve 69 opening in the direction of the pump cylinder.

The pump cylinder is arranged to contain a piston of 45 any ordinary construction and arranged to operate in any ordinary manner, and one end of the pump is con-

nected by a pipe 70 to the feed tube 21 of the lower flashers, and the other end of the cylinder is connected by a pipe 72 to the feed pipe 22 of the upper set of flashers. Each of these pipes 70 and 72 contains a one way 50 check valve 73, opening in the direction of the flashers. In the operation of this portion of the mechanism the water and air will be drawn alternately from the chambers 64 and 65 into the pump cylinder, and from thence will be discharged through the pipes to the flashers the 55 supply of mingled air and water being forced alternately to the upper and lower flashers, and the water instantly flashing into steam which is afterwards conveyed through the superheating coils and finally passes out through the main steam pipe to the engine or other 60 point where it is to be utilized.

I claim:

1. In a flasher, the combination with a casing, of a pair of banks of flasher tubes arranged therein, the tubes of one bank being staggered with relation to those of the other bank, a bank of superheating tubes arranged above the flasher tubes and receiving the steam from both banks of the latter, and means for forcing jets of water alternately into the upper and lower banks of flasher tubes. 65

2. In a flasher, the combination with a casing, of a pair of superposed banks of flasher tubes arranged therein, the tubes of one bank being staggered with relation to those of the other bank, a bank of superheating tubes arranged above the flasher tubes and receiving the steam from both banks of flasher tubes, the tubes of the superheating bank being staggered with relation to the flasher tubes, of the other bank, and means for forcing a mingled stream of air and water alternately into the banks of flasher tubes. 70

3. In a flasher, the combination with a casing, of a pair of banks of flasher tubes arranged therein, a bank of superheating tubes arranged above the flasher tubes and receiving the steam therefrom, a superheating coil arranged above and connected to the superheating tubes, an additional coil arranged above the superheating coil and forming a feed water heater, means for forcing water through the feed water heater, means for alternately forcing water from the feed water heater to the banks of flasher tubes, and means for intermingling air with the water in advance of its entrance to such flasher tubes. 80

In testimony that I claim the foregoing as my own, I have hereto affixed my signature in the presence of two witnesses.

SAMUEL S. DAVIS.
